PER

United States Patent Office.

ARNOUT CANNON, JR., OF POUGHKEEPSIE, NEW YORK.

Letters Patent No. 90,422, dated May 25, 1869.

IMPROVED DUMB WAITER.

The Schedule referred to in these Letters Patent and making part of the same.

To all whom it may concern:

Be it known that I, ARNOUT CANNON, Jr., of the city of Poughkeepsie, in the county of Dutchess, and State of New York, have invented a new and useful Improvement in Dumb Waiters; and I do hereby declare that the following is a full, clear, and exact description thereof, which will enable others skilled in the art to make and use the same, reference being had to the accompanying drawing, forming part of this specification, in which—

Figure 1 is a front view of my improved dumb waiter, the front wall of the well being removed.

Figure 2 is a horizontal section of the well, taken through the line *x-x*, fig. 1, and showing a top view of the mechanism.

Similar letters of reference indicate corresponding parts.

My invention has for its object to improve the construction of dumb waiters, so as to make them stronger, safer, more durable, and more easily controlled, so that they will remain stationary in any position in which they may be placed, both when loaded and when empty; and

It consists in the construction, combination, and arrangement of various parts of the hoisting-device, as hereinafter more fully described.

A is the well, in which the waiter moves up and down.

B is the waiter, in which the articles to be carried up and down are placed, and which is constructed in the ordinary manner.

C is the rope, by which the waiter *B* is suspended, and the end of which is securely attached to the top of the said waiter *B*.

As the rope *C* passes up, it passes over the guide-pulley *D*, around the large pulley, *E*, attached to the shaft *F*, around the guide-pulley *G*, over the pulley *H*, and into the weight-chamber *I*, where it is attached to the weight *J*, which should be about one and a half time heavier than the waiter *B*.

K is the hoisting-wheel, which is attached to the same shaft, *F*, with the large pulley, *E*, as shown in fig. 2.

L is the endless hoisting-rope, which passes over the hoisting-wheel *K*, down along the sides of the well *A*, around the guide-pulleys *M*, and around the weight-pulley *N*.

The pulley *N* should be from eight to twelve pounds' weight, more or less, and its journals enter and work in slots in standards *O*, which are placed and secured in the lower part of the well *A*, in such positions that the axis of the pulley *N* may be in the same vertical plane with the axis of the hoisting-wheel *K*, so that the weighted pulley *N* may not only keep the hoisting-rope *L* taut, but may act as a balance-weight, in connection with the friction of the rope *C*, to hold the waiter stationary at any desired elevation.

The grooves in the hoisting wheel *K* and in the large pulley *E*, should be made V-shaped, to prevent the ropes *L* and *C* from slipping.

Having thus described my invention,

What I claim as new, and desire to secure by Letters Patent, is—

1. The combination of the heavy, or weighted pulley *N* with the endless hoisting-rope *L* and hoisting-wheel *K*, substantially as herein shown and described, that is to say, in such a way that the axis of the suspended heavy pulley *N* may be in the same vertical plane with the axis of the hoisting-wheel *K*, as and for the purposes set forth.

2. The combination and arrangement of the rope *C*, guide-pulley *D*, large pulley *E*, guide-pulleys *G* and *H*, and weight *J*, with each other, with the hoisting-wheel *K*, and waiter *B*, substantially as herein shown and described, and for the purpose set forth.

ARNOUT CANNON, JR.
